UNITED STATES PATENT OFFICE

164,441

PHOTOGRAPH ALBUM

Henry Orzechowski, Pawtucket, and Benjamin
Orzechowski, Central Falls, R. I.

Application October 19, 1949, Serial No. 5,572

Term of patent 14 years

(Cl. D61—1)

To all whom it may concern:

Be it known that we, Henry Orzechowski and Benjamin Orzechowski, both citizens of the United States, residing at Pawtucket and Central Falls, respectively, in the county of Providence and State of Rhode Island, have invented a new, original, and ornamental Design for a Photograph Album, of which the following is a specification, reference being had to the accompanying drawing, forming part thereof.

Fig. 1 is a perspective view of a photograph album, showing our new design; and

Fig. 2 is a similar view, the cover being in open position.

We claim:

The ornamental design for a photograph album, as shown.

HENRY ORZECHOWSKI.
BENJAMIN ORZECHOWSKI.
